UNITED STATES PATENT OFFICE

WILLIAM R. GREER, JR., OF WOODHAVEN, NEW YORK, ASSIGNOR TO ORANGE LIGHTING FIXTURE MANUFACTURING CO., A CORPORATION OF NEW JERSEY

DESIGN FOR A LIGHTING-FIXTURE WALL BRACKET

Application filed November 25, 1929. Serial No. 33,553. Term of patent 7 years.

To all whom it may concern:

Be it known that I, WILLIAM R. GREER, Jr., a citizen of the United States, and a resident of Woodhaven, county of Queens, and State of New York, have invented a new, original, and ornamental Design for a Lighting Fixture Wall Bracket, of which the following is a specification, reference being had to the accompanying drawing, forming a part hereof.

In the drawing:

I claim:

The ornamental design for a lighting fixture wall bracket substantially as shown.
